UNITED STATES PATENT OFFICE.

JOE A. HUGHES AND THOMAS E. HERINGTON, OF MALLARD, IOWA.

UMBRELLA.

1,344,132.

Specification of Letters Patent. Patented June 22, 1920.

Application filed August 19, 1919. Serial No. 318,487.

To all whom it may concern:

Be it known that we, JOE A. HUGHES and THOMAS E. HERINGTON, citizens of the United States, residing at Mallard, in the county of Palo Alto and State of Iowa, have invented certain new and useful Improvements in Umbrellas, of which the following is a specification.

This invention relates to umbrellas and more particularly to an apparatus forming the frame of an umbrella or parasol which will be readily collapsible so that the umbrella or parasol may be packed in a relatively small space such as a trunk or valise.

15 A further object of the invention is to provide a collapsible umbrella which will have the appearance of an ordinary umbrella when in use and which will have the collapsible parts arranged so that they will 20 be held securely in the desired operative position when the umbrella is in use.

A further object of this invention is the provision of a device of this character which consists of comparatively few parts, but is 25 simple in construction, but durable and well adapted to withstand the rough usage to which devices of this character are ordinarily subjected.

For a full description of the invention and 30 the advantages and merits thereof, reference is to be had to the following description and accompanying drawings, in which:—

Figure 1 is a longitudinal section of the umbrella constructed in accordance with our 35 invention and showing the parts in operative position.

Fig. 2 is a longitudinal section of the structure in collapsed position.

Fig. 3 is an enlarged section, parts being 40 shown in elevation of one of the collapsible ribs of the umbrella, and the connections therefor.

Fig. 4 is an enlarged elevation of a portion of the structure shown in Fig. 3, also 45 having parts shown in section, and showing the parts in open or operative position.

Fig. 5 is a bottom view of the structure shown in Fig. 4.

Fig. 6 is a section on the line 6—6 of 50 Fig. 4.

Fig. 7 is a side elevation of a portion of the shaft or handle of the umbrella.

Fig. 9 is a section taken on the line 9—9 of Fig. 2, looking in the direction of the arrow, and

55 Fig. 8 is a central vertical section showing the construction of the latches.

Referring to the drawings wherein is illustrated the preferred form of our invention, in which like numerals of reference indicate like or corresponding parts throughout the several views, the shaft comprises a series of tubular members 1, 2 and 3 which are telescopically connected together and which are provided with longitudinal slots 60 4 each of which receives a pin 5 carried by one of the corresponding collapsible parts to permit telescopic movement of the sections in order that the handle may be collapsed to a relatively short length as shown 65 in Fig. 2. The small upper member 3 has one end provided with a ferrule 6 to which are hingedly connected the ribs 7 which are normally straight but are adapted to flex or bend in the usual manner when moved into 70 operative position. The shaft also has slidably mounted thereon a sleeve 8 which is provided with a plurality of ears receiving pivot pins 9 whereby the braces 10 may be connected to the movable sleeve. Each rib 75

comprises the hingedly connected sections 12 and 13. The section 12 has mounted thereon a sliding member 14 which is provided with opposite ears 15 between which one end of one of the brace members 10 is 80 received and the brace member is pivotally connected to the ears 15 by means of a pin 16. The section 13 has one end curved as shown in Fig. 4 and the terminal of the curved portion is also joined to the pivot 85 pin 16 while the opposite end of the section 13 is apertured as indicated at 17 whereby the cover of the umbrella may be attached in the usual manner. A sleeve 18 is carried by the outer end of the section 12 of each 90 rib and the section 13 of the rib is extended through this sleeve and is adapted to slide therethrough. The member 14 slides on the member 12 and each brace member 10 together with the corresponding section of the 95

adjacent rib, indicated at 13 are adapted to move together, so that when the member 14 is longitudinally moved on the section 12, the parts 10 and 13 will move to the position 100

shown in Figs. 2 and 3 of the drawing, so that the parts will be substantially parallel with the shaft of the umbrella.

In order that the sleeve 8 may be held in operative position when the umbrella is raised, the section 3 of the shaft is provided with an elongated slot 20 and a pair of spring latches 21 are mounted in position to spring outwardly through the slot 20 when the umbrella shaft is extended. Normally, when the umbrella shaft is collapsed, the section 2 of the shaft incloses the section 3 thereby maintaining the two spring latches 21 inwardly as shown in Fig. 8. When the umbrella shaft is extended, however, the two latches 21 spring outwardly and their ends are spaced apart sufficiently to embrace the sleeve 8 as shown in Fig. 1 whereby the sleeve will be held in the desired fixed position in the upper end of the section 3. This maintains the brace member 10 in extended position and consequently the corresponding ribs will be extended so that the umbrella will be firmly held in open position.

The foregoing description and accompanying drawings have reference to what might be considered to be the approved or preferred form of our invention. We desire it to be understood that we may make such changes in the construction, combination

and arrangement of parts, materials, dimensions, et cetera, as may prove expedient and fall within the scope of the appended claim.

Having thus fully described our invention what we claim as new and desire to secure by Letters Patent, is:—

A collapsible umbrella comprising a series of telescopically connected sections, a ferrule on the upper end of the upper section, a sleeve slidably mounted on said upper section, means provided on said upper section for holding said sleeve in a desired position, ribs hingedly mounted upon said ferrule, extension ribs hingedly connected to said ribs, a sliding member mounted upon said ribs and provided with opposite ears, braces pivotally connected to said ears and said sleeves, said extension ribs having their inner ends curved and pivotally connected to said braces, a collar fixedly mounted upon the outer ends of said ribs, thereby holding said extension ribs in alinement with said ribs when extended and parallel to said ribs when folded.

In testimony whereof we affix our signatures in presence of two witnesses.

JOE A. HUGHES.
THOMAS E. HERINGTON.
